UNITED STATES PATENT OFFICE.

PETER CARNEGIS, OF WASHINGTON, DISTRICT OF COLUMBIA.

BOAT-PROPELLING MECHANISM.

1,318,844.

Specification of Letters Patent.

Patented Oct. 14, 1919.

Application filed October 27, 1917. Serial No. 198,843.

To all whom it may concern:

Be it known that I, PETER CARNEGIS, a subject of Greece, residing at Washington, in the District of Columbia, have invented 5 certain new and useful Improvements in Boat-Propelling Mechanism, of which the following is a specification.

This invention relates to marine propulsion, and it is the dominant object of the 10 invention to provide an improved manually operable boat propelling mechanism, whereby a boat can be driven over the surface of a body of water at an appreciable speed and with but little effort or exertion 15 upon part of the operator.

Another and equally important object of the invention is to provide a propelling mechanism whereby a boat provided with the same can be driven in a reverse direction 20 as the occasion arises.

The improvements in the details and arrangement of parts will be apparent from an inspection of the accompanying drawings, in connection with the specific description 25 hereinafter contained, and wherein the preferred embodiment of the invention is disclosed for the purpose of imparting a full understanding of the same.

In the drawings:—

30 Figure 1 is a top plan of the invention applied to a boat having parts broken away, and,

Fig. 2 is a vertical section therethrough.

Having more particular reference to the 35 drawings and in connection with which like reference characters will designate corresponding parts in the several views, 1 represents a boat provided with the improved propelling mechanism, the boat having a 40 rudder 2 arranged thereon, which rudder is connected with suitable steering gear 3.

A propeller shaft 4 is arranged longitudinally of the rear portion of the boat 1 and has a portion of the same arranged in suitable 45 bearings 5 and extended for a distance slightly beyond the boat whereby a propeller 6 can be mounted thereon.

Bearing pillars 7 are arranged in the bottom of the boat 1 and rotatably support 50 the opposite extremities of a crank shaft 8, which as will be noted, has sprocket wheels

9 arranged thereon. Sprocket chains 10 are passed about the several sprocket wheels 9 and about smaller sprocket wheels 11 journaled in bearings 12 arranged adjacent the bearing pillars 7; it being noted in this connection, that the said bearings 12 are arranged in disaligned positions, the purpose of which will be subsequently apparent. Mounted on the shafts carrying the 60 several sprocket wheels 11 are beveled gears 13 which constantly mesh with a double faced beveled gear 14 carried upon the adjacent end of the propeller shaft 4.

Pitman rods 15 are pivotally engaged 65 with the crank shaft 4 and with foot pedals 16, which pedals in turn are pivotally mounted on bases 17 secured to the flooring of the boat at a point convenient to the operator's seat 18.

In operation, the operator is seated on the seat 18 and engages the foot pedals with his feet and alternately moves the same. Obviously, such motion will cause rotation of the crank shaft 4 and as a consequence, 75 rotary motion will be imparted by way of the sprocket chains 10 to the sprocket wheels 12 and from them by way of the beveled gear connected to the same to the propeller shaft, thus rotating the propeller 80 and driving the boat over a surface of water. To reverse the direction of travel of the boat, it is only necessary to reverse the operation of the foot pedals.

Manifestly, the construction shown is capable of considerable modification and such modification as is within the scope of my claim, I consider within the spirit of my invention.

I claim: 90
In combination with a boat and a propeller shaft therefor, a screw propeller carried by the shaft, a double faced bevel gear wheel on said shaft, parallel stub-shafts supported in the boat at right angles to the 95 propeller shaft and on opposite sides of the gear wheel, bevel gear wheels carried by the stub-shafts arranged forwardly and rearwardly and at diametrically opposed points of the double faced bevel gear wheel, 100 the second mentioned gear wheels meshing with the opposed sets of gear teeth of the

double faced gear wheel, spaced bearing pillars arranged in the boat, a crank shaft mounted in said pillars, permanent driving connections between each stub-shaft and 5 the crank shaft, rods connected with the crank shaft, and pivotal pedals supported in the boat and connected with the rods

whereby the crank and propeller shafts may be rotated in either direction to propel the boat, forwardly or rearwardly.

10

In testimony whereof, I affix my signature hereto.

PETER CARNEGIS.
